ABSTRACT

A safety container and closure cap unit therefor includes means for detachably latching or attaching the safety closure cap unit to the neck portion of the container body by manually inserting the safety closure cap unit on the neck portion of the container body and imparting rotational movement to the closure cap unit in the form of a partial turn or revolution without manipulation of any parts or instrumentalities in the closure cap unit or in the closure cap housing or on the container body other than the rotational movement of the closure cap unit itself. The closure cap unit may be removed from the neck portion of the container body by the simultaneous application of manual pressure on a plurality of manually operable means located at a plurality of pressure points spaced from each other on the periphery of the closure cap housing unit and simultaneously therewith imparting rotational movement in the form of a partial turn or revolution to the closure cap unit in a direction opposite to the direction of movement imparted to the closure cap unit by the said first partial turn or revolution, and then manually withdrawing the closure cap unit from the neck portion of the container body. A fluidtight seal is effected between the closure cap unit and the neck portion of the container body as the closure cap unit is thus installed upon the neck portion of the container body.

**SAFETY CONTAINER AND CLOSURE CAP UNIT
THEREFOR**

OBJECTS

An object of the present invention is to provide a new and improved combination safety container and closure cap unit therefor in which the closure cap unit may be readily installed upon the neck portion of the container body by manually applying the closure cap unit over the neck portion of the container body and manually imparting rotational movement in the form of a partial turn or revolution thereto without the necessity for manipulating any instrumentalities or parts on either the closure cap unit or the container body, other than the closure cap unit itself, so that the manner of application of the closure cap unit to the neck portion of the container body corresponds very closely to the manner in which a conventional screw-threaded closure cap unit is applied to the screw-threaded neck portion of a bottle or like container.

Another object of the invention is to provide a new and improved combination safety container and closure cap unit therefor in which a first latching or attaching means on the neck portion of the container body and a second latching or attaching means on the closure cap unit are moved into coaxing latching or attaching engagement with each other to latch or attach the closure cap unit to and upon the neck portion of the container body by manually inserting the closure cap unit onto the neck portion of the container body and manually imparting rotational movement thereto in the form of a partial turn or revolution thereto without the necessity for manipulating any other parts or instrumentalities on either the closure cap unit or the container body.

An additional object of the present invention is to provide a new and improved combination safety container and closure cap unit therefor in which the closure cap unit embodies manually operable unlatching means for moving the second latching or attaching means on the closure cap out of coaxing latching or attaching engagement with the first latching or attaching means on the neck portion of the container body, and in which the closure cap unit embodies manually operable restraining means for preventing manual movement of the said unlatching means until manually operable restraining means is actuated so that the closure cap unit may be removed from the neck portion of the container body only by simultaneously applying manual pressure with the fingers of one hand to the said manually operable unlatching means and to the said manually operable restraining means for the said unlatching means while holding the container body with the other hand and imparting rotational movement to the said closure cap unit upon and relative to the said container.

An additional object of the present invention is to provide a new and improved combination safety container and closure cap unit therefor which is particularly adapted for use in the packaging and sale of pharmaceutical preparations, tablets, drugs, medicines, and like products which are dangerous to children since the new combination safety container and closure cap unit therefor is so designed and constructed that the safety closure cap unit therefor cannot be removed from the container body by small children.

A further object of the invention is to provide in the new safety container and closure cap unit therefor novel means for holding a second latching or attaching means on the closure cap unit out of coaxing latching or attaching engagement with a first latching or attaching means which is provided in the upper end or neck portion of the container body during the time the closure cap unit is manually and rotatably moved upon and relative to the upper end or neck portion of the container body from an initial position to a final position in which the said first latching or attaching means and the said second latching or attaching means coact to detachably latch or attach the said closure cap unit to and upon the said upper end or neck portion of the said container.

An additional object of the invention is to provide in the new safety container and closure cap unit therefor novel

manually operable means carried by the said closure cap unit for unlatching the said second latching or attaching means on the said closure cap unit from the said first latching or attaching means on the upper end or neck portion of the body of the container so that the said closure cap unit may be manually removed from the upper end or neck portion of the container body by manually imparting rotational movement to the closure cap unit upon and relative to the upper end or neck portion of the container body.

Still another object of the present invention is to provide therein novel means for guiding the second latching or attaching means in the closure cap unit into and out of coaxing latching or attaching engagement with the first latching or attaching means on the upper end or neck portion of the container body while the closure cap unit is being installed upon and latched or attached to and removed from the upper end or neck portion of the container body.

Another object of the invention is to provide in the new combination safety container and closure cap unit therefor novel means for effecting a fluidtight seal between the closure cap unit and the upper end or neck portion of the container body as the closure cap unit is installed upon and latched to the upper end or neck portion of the container body.

A further object of the invention is to provide a new and improved combination container and safety closure cap unit therefor which is relatively simple and inexpensive in construction and in which the closure cap unit may be readily assembled upon the neck portion of the container body in rapid assembly line packaging operations without the necessity for special assembling equipment other than assembly equipment which is comparable to that used in assembly line packaging operations employing conventional screw-threaded closure caps and bottles or like containers having screw-threaded neck portions for the reception of the screw-threaded closure cap units.

Other objects will appear hereinafter.

DESCRIPTION OF FIGURES IN THE DRAWINGS

FIG. 1 is an elevational view of a preferred embodiment of the new combination safety container and closure cap unit therefor in assembled position;

FIG. 2 is an elevational view of the new safety container and closure cap unit therefor as seen from the right hand side in FIG. 1;

FIG. 3 is a top plan view of the new safety container and closure cap unit therefor;

FIG. 4 is an enlarged fragmentary vertical sectional view of line 4—4 in FIG. 3;

FIG. 5 is an enlarged fragmentary vertical sectional view on line 5—5 in FIG. 3;

FIG. 6 is an enlarged fragmentary vertical sectional view on line 6—6 in FIG. 3;

FIG. 7 is a fragmentary elevational view showing part of the container body and the neck portion thereof and showing the closure cap unit removed from but disposed above the neck portion of the container body;

FIG. 8 is a horizontal sectional top plan view through the closure cap unit on line 8—8 in FIG. 7;

FIG. 9 is a horizontal sectional top plan view through the closure cap unit on line 9—9 in FIG. 7;

FIG. 10 is a bottom plan view of the closure cap unit on line 10—10 in FIG. 7;

FIG. 11 is a horizontal sectional top plan view of the neck portion of the container body on line 11—11 in FIG. 7;

FIG. 12 is a central vertical sectional view of the inner body member of the closure cap unit showing part of the second latching or attaching means embodied therein and also showing part of the means embodied therein for unlatching the latching or attaching means on the closure cap unit from the latching or attaching means on the neck portion of the container and also showing part of the restraining means for the said unlatching means;

FIG. 13 is a fragmentary central vertical sectional view of the outer body member of the closure cap unit showing the transverse or horizontal sealing wall embodied therein;

FIG. 14 is a fragmentary central vertical sectional view illustrating the construction of the neck portion of the container body;

FIG. 15 is an enlarged fragmentary vertical sectional view showing the closure cap unit mounted on and latched or attached to the neck portion of the container body;

FIG. 16 is a fragmentary sectional view similar to FIG. 15 but showing the restraining means for the second latching or attaching means on the closure cap unit moved into position to enable the said second latching or attaching means on the closure cap unit to be unlatched from the first latching or attaching means on the neck portion of the container body;

FIG. 17 is a fragmentary vertical sectional view similar to FIG. 16 but showing the second latching or attaching means on the closure cap unit moved out of latching or attaching engagement with the first latching or attaching means on the neck portion of the container body and showing the closure cap unit in a position in which it may be removed from the neck portion of the container body by imparting rotational movement in the form of a partial turn or revolution thereto;

FIG. 18 is a side elevational view of the inner body member of the closure cap unit and illustrating the first latching or attaching means and the unlatching means embodied therein;

FIG. 19 is a side elevational view of the inner body member of the closure cap unit shown in FIG. 18 as seen from the right hand side in FIG. 18;

FIG. 20 is a top plan view of the inner body member of the closure cap unit shown in FIGS. 18 and 19;

FIG. 21 is a side elevational view of the outer body member of the closure cap unit;

FIG. 22 is a side elevational view of the outer body member of the closure cap unit shown in FIG. 21 as seen from the right hand side in FIG. 21;

FIG. 23 is a top plan view of the outer body member of the closure cap unit shown in FIGS. 21 and 22;

FIG. 24 is a bottom plan view of the outer body member of the closure cap unit shown in FIGS. 21, 22 and 23; and

FIG. 25 is a view partly in elevation and partly in section showing the closure cap unit being applied to and installed upon the neck portion of the container body.

DETAILED DESCRIPTION OF STRUCTURE

A preferred embodiment of the new safety container and closure cap unit therefor is illustrated in the drawings, wherein it is generally indicated at 30 and comprises a generally cylindrical container body 31 having a generally annular upper end or neck portion 32 and a safety closure cap unit generally indicated at 33, and which is adapted to be detachably mounted on the generally annular upper end or neck portion 32 of the container body 31; it being understood that the container body 31 and its upper end or neck portion 32 may take various forms and shapes and sizes or dimensions.

The closure cap unit 33 comprises a generally cylindrical outer body member 34 and a generally annular inner body member 35 which are detachably assembled together for installation upon and removal from the neck portion 32 of the container body 31, as will be described more fully hereinafter.

The outer body member 34 and the inner body member 35 of the closure cap unit 33 may be made of any suitable materials as, for example, molding the same from any suitable synthetic resinous plastic molding material such, for example, as polystyrene, polyethylene, synthetic rubberlike copolymer elastomers, glass, metal, or the like, and the container body 31 and its neck portion 32 may likewise be made of any suitable material such, for example, as glass, metal, synthetic rubberlike copolymer elastomers, synthetic resinous plastic materials, and the like.

The upper end or neck portion 32 of the container body 31 has a first latching or attaching means formed therein as an in-

tegral part thereof for detachably latching or attaching the closure cap unit 33 on and to the neck portion 32 of the container body 31. Likewise, the upper end or neck portion 32 of the container body 31 has a pair of combination guide and camming means formed therein, each of which is generally indicated at 36 (FIG. 7) and includes a pair of irregularly shaped or curvilinear combination guide and camming slots 38 which are spaced circumferentially approximately 180° on the neck portion 32 of the container body 31 (FIG. 11). Each of the combination guide and camming slots 38 has at one end thereof an inlet-outlet 39 which opens at its upper end on the top or upper edge portion 69 of the neck portion 32 of the container body 31. At its other and lower end each of the combination guide and camming slots 38 has an upwardly and generally vertically extending portion in the form of a latching recess 41, the upper end portion 42 of which terminates below the top or upper edge 40 of the upper or neck portion 32 of the container body 31; the latching recesses 41 providing the first attaching or latching means which is embodied in the new combination container and closure cap unit therefor for detachably attaching the closure cap unit 33 to and upon the upper end or neck portion 32 of the container body 31.

A pair of irregularly shaped curvilinear camming surfaces 53 are thus provided in the upper end or neck portion 32 of the container body 31 above the combination guide and camming slots 38, and an additional curvilinear cam surface is provided by the upper edge portion 68 of each of the combination guide and camming slots 38 (FIG. 7).

30 The inner body member 35 of the closure cap unit 33 includes a generally annular body 43 which includes a generally annular side wall 44 and a top wall 45. The inner body member 35 also includes a second latching or attaching means in the form of a plurality, shown as a pair, of resilient depending latching or attaching tongue members 46 which are formed integrally with and depend from the generally annular side wall 44 thereof at spaced radial intervals of preferably 180° thereon, each of the resilient latching or attaching tongue members 46 having a radially inwardly extending lower latching or attaching end portion 47 (FIGS. 6, 12, 15, 16, 17, 18, 19 and 25).

The inner body member 35 of the closure cap unit 33 has a plurality, shown as a pair, of manually operable unlatching members 48 which are formed integrally therewith on the 45 outer side of the generally annular side wall 44 thereof and at spaced intervals of preferably 180° radially therearound. Each of the manually operable unlatching members 48 projects radially outwardly of the generally annular side wall 44 of the inner body member 35 and an upwardly extending recess 49 is formed in the inner body member 35 of the closure cap unit 33 between each of the manually operable unlatching members 48 and an adjacent motion limiting restraining means in the form of a wall portion 50 of the generally annular side wall 44 of the inner body member 35, for a reason which will be pointed out presently (FIGS. 4, 12, 15, 16, 17 and 18). Each of the restraining wall portions 50 of the generally annular side wall 44 of the inner body member 35 of the closure cap unit 33 and each of the adjacent manually operable unlatching members 48 has a flexible interconnecting web portion 52 by 50 which it is joined at its upper end to the generally annular side wall 44 of the inner body member 35 of the closure cap unit 33, immediately below the top wall 45 of the inner closure body member 35, and the flexibility of each of the restraining wall portions 50 and of the adjacent manually operable unlatching members 48 is enhanced by the provision of a pair of vertically extending slots 52 which are formed in the generally annular side wall 44 of the inner closure body member 35 at the sides of each of the manually operable unlatching members 48 (FIGS. 2 and 19).

The outer body member 34 of the closure cap unit 33 includes a generally annular side wall 54 and a transversely or horizontally extending sealing wall 55 which extends across the outer closure body member 34 between the upper and lower ends thereof (FIGS. 4, 5, 6, 8, 9, 10, 13, 15, 16, 17, 24

and 25). The generally annular side wall 54 of the outer closure body member 34 has a pair of vertically extending slots 56 formed therein which are spaced apart circumferentially on the generally annular side wall 54 of the outer body member 34, a distance corresponding to the spacing of the manually operable unlatching members 48, that is, preferably 180°. Each of the manually operable unlatching members 48 on the inner body member 35 of the closure cap unit 33 projects through and works in a corresponding one of the slots 56 in the generally annular side wall 54 of the outer body member 34 when the inner body member 35 and the outer body member 34 of the closure cap unit 33 are assembled together. As shown in FIGS. 2 and 22, the slots 56 in the generally annular side wall 54 of the outer closure body member 34 open at their upper ends at the upper edge 57 of the generally annular side wall 54 of the outer closure body member 34.

As shown in FIGS. 6, 9, 10, 15, 16, 17 and 25, each of the manually operable latching or attaching members 46 on the inner closure body member 35 projects downwardly through and is vertically slidably movable in a slot 58 which is formed in the transverse horizontal sealing wall 55 of the outer closure body member 34. A pair of upwardly extending stop or restraining boss and cam members 61 are formed on the generally horizontal or transverse sealing wall 55 of the outer body member 34 and these restraining boss members 61 are disposed in alignment with the manually operable restraining members 50 on the inner closure body member 35 when the inner end outer body members 35 and 34, respectively, of the closure cap unit 33 are in assembled relationship, as shown in FIGS. 4 and 15. Each of the combination restraining boss and cam members 61 has a downwardly and inwardly extending cam surface 71 formed on its inner surface, for a reason which will be pointed out hereinafter (FIGS. 4, 13, 15, 16, 17 and 25).

As shown in FIGS. 4, 5, 6, 13, 15, 16, 17 and 25, the generally annular side wall 54 and the horizontal or transverse sealing wall 55 of the outer body member 34 of the closure cap unit 33 cooperate to provide a generally cylindrical cavity or recess 60 for the reception of the inner body member 35 of the closure cap unit 33 when the inner body member 35 and the outer body member 34 are in assembled relationship.

The top wall 45 of the inner closure body member 35 has a centrally arranged finger grip or finger-receiving portion 62 formed therein, which provides one of the three manual pressure points which are located at spaced intervals on the peripheral surface of the closure cap unit 33, for a reason which will be pointed out hereinafter.

A radially inwardly extending guide member in the form of a boss 63 is formed integrally with and is an extension of the generally annular side wall 54 of the outer body member 34 of the closure cap unit 33 below the transverse or horizontal sealing wall 55 thereof and at one side of the corresponding slot 58, the bottom surface of each of these guide members 63 being substantially coplanar with the bottom surface of the generally annular side wall 54 of the outer closure body member 34 (FIGS. 13, 15 and 25).

The radially inner surface of the generally annular side wall 54 of the outer closure cap body member 34 is dished out to provide a pair of radially outwardly extending recesses 64 therein, each of these recesses 64 being in vertical alignment with and being disposed radially outwardly of the corresponding one of the slots 58 in the transverse or horizontal wall 55 in the outer closure cap body member 34 (FIGS. 6, 10, 13, 15, 16, 17 and 25) for a reason which will be pointed out hereinafter.

A pair of vertically extending slots 65 are formed in the generally annular side wall 54 of the outer closure body member 34, radially outwardly of but in generally vertical registration with the vertically extending slots 58 in the transverse or horizontal sealing wall 55 of the outer closure body member 34, the lateral edges of each of these slots 65 being defined by a vertically extending surface 66 of one of the guide members 63 and an adjacent vertically extending sur-

face 67 of the generally annular side wall 54 of the outer closure body member 34 (FIGS. 10 and 24). As best shown in FIGS. 10 and 24, each of the vertically extending slots 65 in the outer side wall 54 of the outer closure body member 34 is closed at its radially outer end by a relatively thin wall portion 71 of the generally annular side wall 54 of the outer closure body member 34, each of the relatively thin wall portions 71 being disposed radially outwardly of the corresponding one of the radially outwardly extending recesses 64 (FIG. 10).

OPERATION

In the use of the new safety container and closure cap unit therefor the generally annular inner closure body member 35 is manually assembled within the generally cylindrical cavity or recess 60 in the generally cylindrical outer body member 34, and the resilient latching or attaching arm members 46-47 are projected downwardly through the slots 58 in the transverse or horizontal sealing wall 55 of the outer body member 34 and with the manually operable unlatching members 48 being disposed in and projecting outwardly of the vertically extending slots 56 in the generally annular side wall 54 of the outer closure body member 34.

When the inner body member 35 and the outer body member 34 of the closure cap unit 33 are thus assembled the lower and radially inwardly extending latching end portions 47 of the flexible, resilient latching or attaching members 46 project downwardly through the slots 58 in the transverse or horizontal sealing wall 55 of the outer closure body member 34 with the radially inwardly extending lower end portions 47 of the flexible, resilient latching or attaching members 46 disposed in the slots 65 which are formed in the generally annular side wall 54 of the outer closure body member 34 between the vertically extending surfaces 66 of the guide members 63 and the vertically extending surfaces 67 of the generally annular side wall 54 of the outer closure body member 34 (FIG. 10). When the inner closure body member 35 and the outer closure body member 34 of the closure cap unit are thus assembled the lower surfaces of the inwardly extending lower end portion 47 of the flexible, resilient latching or attaching members 46 are disposed in a generally horizontal plane which lies immediately above the upper horizontal surfaces of the guide members 63 (FIG. 15).

When the inner and outer closure body members 35 and 34, respectively, of the closure cap unit 33 are thus assembled the assembled closure cap unit 33 may be inserted upon and detachably latched or attached to the upper end or neck portion 32 of the container body 31 by manually aligning the flexible resilient latching or attaching members 46-47, and the guide members 63, with the upper end or inlet-outlet portions or mouths 39 of the combination guide and camming slots 38 which are formed in the neck portion 32 of the container body 31 (FIG. 7) and then manually pressing downwardly on the closure cap unit 33 so as to project the guide members 63 downwardly into and through the inlet or mouths 39 of the combination guide and camming slots 38. The assembled closure cap unit 33 may then be readily manually latched or attached to the neck portion 32 of the container body 31 by imparting rotational movement in the form of a partial turn or revolution thereto, (counterclockwise, FIGS. 7, 8 and 9) thereby causing the guide members 63 to travel in the curvilinear combination guide and camming slots 38 from their inlet portions or mouths 39 toward their outlet ends 36 (FIG. 7). During this movement the lower and inwardly extending latching or attaching end portions 47 of the flexible resilient latching or attaching members 46 engage and ride over the radially outer cam surfaces 53 which are formed on the peripheral surface of the neck portion 32 of the container body 31, thereby forcing the lower and latching or attaching end portions 47 of the flexible resilient latching or attaching members 46 radially outwardly in the slots 65 while, at the same time, forcing the flexible resilient latching or attaching members 47 radially outwardly in the slots 58 in the transverse or

horizontal sealing wall 55 of the outer closure body member 34, and thereby placing the flexible resilient latching or attaching members 46-47 under tension.

Accordingly, when the flexible resilient latching or attaching members 46-47 reach the outer end portions 36 of the curvilinear combination guide and camming slots 38 in the neck portion 32 of the container body 31, the radially inwardly extending and then tensioned lower latching or attaching end portions 47 of the flexible, resilient, latching or attaching members 46-47 move or snap under their own tension and resiliency radially inwardly into the upwardly extending latching recesses 41 in the curvilinear combination guide and camming slots 38, and into engagement with the upper edge portion 42 thereof, thereby detachably latching or attaching the assembled closure cap unit 33 to and upon the neck portion 32 of the container body 31 (FIGS. 4, 5, 6 and 15).

When the closure cap unit 33 is thus assembled upon and detachably latched or attached to the neck portion 32 of the container body 31, as shown in FIGS. 4, 5, 6 and 15, the closure cap unit 33 cannot be manually removed from the neck portion 32 of the container body 31 by manually pulling upwardly thereon for the reason that the inwardly extending lower latching or attaching end portions 47 of the flexible, resilient latching or attaching members 46 are engaged in the upwardly extending latching recesses 41 at the outer ends of the combination guide and camming slots 38 and abut against the upper edge portions 42 thereof (FIGS. 7 and 15).

It will be noted that when the closure cap 33 is thus installed upon and latched or attached to the neck portion 32 of the container body 31 the restraining members 50 on the radially inner surface of the generally annular side wall 54 of the upper closure body member 35 are disposed in abutting engagement with the corresponding restraining or stop members 61 which are formed on the upper surface of the transverse or horizontal sealing wall 55 of the outer closure body member 34 so that the inner closure body member 35 cannot be moved downwardly relative to or separated from the outer closure body member 34 and the inner closure body member 35 cannot be moved upwardly relative to the outer body member 34 by reason of the latching or attaching engagement of the inwardly extending lower end portions 47 of the flexible, resilient latching or attaching members 46 (on the inner closure body member 34) in the latching recesses 41 in the upper end or neck portion 32 of the container body 31.

As the closure cap unit 33 is thus assembled on and detachably latched or attached to the neck portion 32 of the container body 31, the guide members 63 on the outer closure body member 34 travel through the curvilinear combination guide and camming slots 38 and engage the curved upper camming edge surfaces 68 thereof, thereby exerting a camming action on the closure cap unit 33 and thus forcing the central portion of the transverse or horizontal sealing wall 55 of the outer closure body member 34 downwardly into fluid-tight sealing engagement with the upper edge portion 40 of the neck portion 32 of the container body 31.

It will be noted that whereas the closure cap unit 33 may be readily installed upon and detachably latched or attached to the neck portion 32 of the container body 31 by the simple operation of manually applying the closure cap unit 33 over and onto the neck portion 32 of the container body 31 and then manually imparting rotational movement in the form of a partial turn or revolution thereto, and without the need for or use or manipulation of any manually operable instrumentalities or parts on either the closure cap unit or in the neck portion of the container body, or other operation, the removal of the closure cap unit 33 from the neck portion 32 of the container body 31 requires that the container body 31 be held in one hand while manual pressure is applied simultaneously with the fingers of the other hand to a plurality of manually operable members 48-48-62 located at a plurality of pressure points 48-48-62 (shown as three) spaced from each other on the peripheral surface of the closure cap unit 33, as will be described presently.

Thus, when it is desired to remove the assembled closure cap unit 33 from the neck portion 32 of the container body 31, this may be accomplished by holding the container body 31 in one hand and applying manual pressure simultaneously with the fingers of the other hand to the three pressure points provided by the manually operable members 48-48-62, which are spaced from each other on the peripheral surface of the closure cap unit 33, that is, by applying manual downward pressure with one finger of the said other hand on the central portion or pressure point 62 of the top wall 45 of the inner closure body member 35 while, at the same time, applying manual pressure radially inwardly with two other fingers of the said other hand on the manually operable unlatching members and pressure points 48-48.

When manual pressure is thus applied simultaneously on the three manually operable members and pressure points 48-48-62 the radially inward pressure thus applied to the unlatching members 48 forces the adjacent restraining members 50 radially inwardly out of abutting engagement with the restraining members or bosses 61 which thereupon enter the recesses 49 which are formed between the manually operable unlatching members 48 and the restraining members 50, (FIGS. 4, 12, 16 and 17), while, at the same time, the downward manual pressure thus applied on the top wall 45-62 of the inner closure body member 35 forces the inner closure body member 35 axially inwardly. This action moves the inwardly angled and latching or attaching members 46-47 axially downwardly out of latching or attaching engagement in and with the latching recesses 42 and into alignment with the combination guide and camming slots 38.

Rotational movement in the form of a partial turn or revolution is then applied manually with the said other hand to the closure cap unit 33, while still applying manual pressure to the three pressure points 62-48-48 with the fingers of the said one hand. This action causes the radially inwardly angled lower end portions 47 of the flexible resilient latching or attaching members 46 to move or rotate in the combination guide and camming slots 38 (left to right, FIG. 7), and during this movement the radially inwardly extending lower end portions 41 of the flexible resilient latching or attaching members 46 and the guide members 63 on the radially inner surface of the generally annular side wall 54 of the outer closure body member 34 travel in the combination guide and camming slots 38 until they reach the inlets-outlets or mouths 39 thereto, whereupon the assembled closure cap unit 33 may then be manually lifted upwardly off the neck portion 32 of the container body 31; the guide members 62 and the lower latching or attaching end portions 47 of the flexible, resilient latching or attaching members 46 passing upwardly through the upper end portions or inlets-outlets 39 of the combination guide and camming slots 38.

When radially inward manual pressure is thus applied to the flexible manually operable unlatching members 48, these manually operable unlatching members 48 and the adjacent restraining members 50 on the generally annular side wall of the inner closure body member 35, flex or bend inwardly at their flexible web connections 51 with the side wall 44 of the inner closure body member 35. During this operation the flexible restraining members 50 on the generally annular side wall 44 of the inner closure body member 35 ride down the tapered inner cam surfaces 70 of the combination restraining and cam members 61, thereby placing the manually operable unlatching members 48 and the adjacent restraining members 50 under tension. However, when manual pressure is released from the central area 62 of the top wall 45 of the inner closure body member 35 the then tensioned flexible, resilient restraining members 50 ride upwardly under the force of their own resiliency and the tension applied thereto, off the cam surfaces 70 of the combination restraining and cam members 61-70, whereupon the manually operable unlatching members 48 and the attached restraining members 50 will flex at the flexible web portion 51 back into their normal or initial position, as in FIG. 4.

It will be noted that the closure cap unit 33 of the new safety container and closure cap unit therefor may be assembled with and upon the upper end or neck portion 32 of the container body 31 by a simple manual movement of the closure cap unit 33 axially downwardly onto the neck portion 32 of the container body 31 followed by rotational movement in the form of a partial turn or revolution of the closure cap unit 33 in generally the same manner as is employed in installing the conventional screw-threaded closure cap upon a conventional screw-threaded neck portion of a conventional bottle or like container, without the need for or manipulation of any manually operable parts or instrumentalities on either the closure cap unit or the neck portion of the container body, other than rotational movement of the closure cap unit itself, thereby enhancing and facilitating not only the use of the new combination container and safety closure cap unit therefor, but also facilitating and simplifying the operation of assembling the parts thereof on conveyors and in packaging lines in manufacturing plants and like places during the operation of filling the container body 31 and applying the new safety closure cap unit 33 thereto.

Likewise, it will be noted that when the new safety closure cap unit 33 is assembled upon and latched or attached to the neck portion 32 of the container body 31, the closure cap unit 33 cannot be removed from the container body 31 by small children for the reason that to remove the closure cap unit 33 from the neck portion 32 of the container body 31, requires the simultaneous application of manual pressure with the fingers of one hand at a plurality of pressure points 48-48-62 on the periphery of the closure cap unit 33 and imparting rotational movement thereto while, at the same time, holding the container body 31 with the other hand, and small children cannot readily perform the operations thus required to remove the closure unit 33 from assembled and latching or attached engagement with the neck portion 32 of the container body 31.

It will thus be seen from the foregoing description, considered in conjunction with the accompanying drawings, that the present invention provides a new and improved safety container and closure cap unit therefor having the desirable advantages and characteristics, and accomplishing its intended objects including those hereinbefore pointed out and others which are inherent in the invention.

We claim:

1. A combination container and closure cap unit therefor, comprising:
  - a. a container body, including
    1. a neck portion;
    - b. a closure cap unit adapted to be detachably attached to the said neck portion of the said container body by manually inserting the said closure cap unit onto the said neck portion of the said container and manually imparting rotational movement to the said closure cap unit relative to the said neck portion of the said container body;
    - c. a first attaching means on the said neck portion of the said container body for detachably attaching the said closure cap unit to the said neck portion of the said container body;
    - d. a second attaching means on the said closure cap unit coacting with the said first attaching means on the said neck portion of the said container body for detachably attaching the said closure cap unit to the said neck portion of the said container body by manually inserting the said closure cap unit onto the said neck portion of the said container body and imparting rotational movement to the said closure cap unit upon and relative to the said neck portion of the said container body;
    - e. manually operable means on the said closure cap unit for manually moving the said second attaching means out of coacting attaching engagement with the said first attaching means whereby the said closure cap unit may be manually installed upon and attached to the said neck portion of the said container body by inserting the said

closure cap unit onto the said neck portion of the said container body and imparting rotational movement to the said closure cap unit without manipulation of the said manually operable means or other parts or instrumentalities on the said closure cap unit or on the said neck portion of the said container body other than the rotational movement applied to the said closure cap unit and the said closure cap unit may be removed from the said neck portion of the said container body by manually operating the said manually operable means and simultaneously therewith applying rotational movement to the said closure cap unit upon and relative to the said neck portion of the said container body in a direction opposite to the direction of rotational movement imparted to the said closure cap unit by the said first rotational movement imparted thereto and without manipulation of any parts or instrumentalities on either the said closure cap unit or the said neck portion of the said container body.

2. A combination container and closure cap unit therefor as defined in claim 1 in which the said closure cap unit includes
  - a. a closure cap housing having
    1. a peripheral surface; and in which
    - b. the said manually operable means includes
      1. a plurality of manually operable members arranged at points spaced from each other on the said peripheral surface of the said closure cap housing.
3. A combination container and closure cap unit therefor as defined in claim 1 which includes
  - a. means for maintaining the said second attaching means on the said closure cap unit out of coacting attaching engagement with the said first attaching means on the said neck portion of the said container body during and until the completion of the said first rotational movement of the said closure cap unit upon and relative to the said neck portion of the said container body.
4. A combination container and closure cap unit therefor as defined in claim 1 in which the said closure cap unit includes
  - a. a closure cap housing including
    1. a side wall; and
    2. a top wall; and in which the said manually operable means includes
      - a. the said top wall of the said closure cap housing; and in which the said manually operable means includes
      - b. a plurality of manually operable members arranged in spaced relationship from each other on the said side wall of the said closure cap housing.
5. A combination container and closure cap unit therefor comprising
  - a. a container body including
    1. an upper end or neck portion;
    - b. a closure cap unit adapted to be mounted upon and detachably attached to the said neck portion of the said container body by applying the said closure cap unit upon the said neck portion of the said container body and manually imparting rotational movement to the said closure cap unit from an initial position to a final and attached position of the said neck portion of the said container body;
    - c. a first attaching means on the said neck portion of the said container body for attaching the said closure cap housing to and upon the said neck portion of the said container body; the said closure cap unit including
    - d. a second attaching means on the said closure cap unit coacting with the said first attaching means to attach the said closure cap unit to and upon the said neck portion of the said container body by applying the said closure cap unit to the said neck portion of the said container body and manually imparting rotational movement to the said closure cap unit upon and relative to the said neck portion of the said container body from the said initial position into the said final and attached position of the said closure cap unit in which the said second attaching means engages the said first attaching means and the said first at-

- taching means and the said second attaching means coact to attach the said closure cap unit to and upon the said neck portion of the said container body; and
- e. means on the said neck portion of the said container body coacting with the said second attaching means on the said closure cap unit for holding the said second attaching means out of coacting attaching engagement with the said first attaching means while the said closure cap unit is being moved from its said initial position to its aforesaid final and attached position on the said upper end or neck portion of the said container body. 10
6. A combination container and closure cap unit therefor as defined in claim 5 in which
- a. the said upper end or neck portion of the said container body is generally annular in shape and has
1. an outer peripheral surface; and in which
- b. the said first attaching means includes
1. a pair of guide slots formed in and spaced circumferentially from each other on the said outer peripheral surface of the said neck portion of the said container body and each having
- a. an inlet; and each having
- b. an end portion providing a latching recess; and in which the said second attaching means on the said closure cap housing includes
- 25
- c. a pair of flexible resilient latching members spaced from each other on the said closure cap unit and each including a lower and latching end portion adapted to engage in one of the said latching recesses in the said upper end or neck portion of the said container body to latch the said closure cap unit to and upon the said upper end or neck portion of the said container body; and in which the said closure cap unit includes
- d. a pair of guide means each adapted to be moved into one of the said guide slots through the said inlet thereto and thence through the said guide slot; and in which the said upper end or neck portion of the said container body includes
- 30
1. a pair of curvilinear cam surfaces spaced circumferentially from each other on the said upper end or neck portion of the said container body and each adapted to be engaged by the said lower and latching end portion of one of the said flexible, resilient latching members to hold the said flexible, resilient latching members out of latching engagement with the said neck portion of the said container body during the time the said closure cap unit is being moved on the said neck portion of the said container body from its aforesaid initial position to its said final and attached position. 35
- 40
7. A combination container and closure cap unit therefor as defined in claim 6 in which
- a. the said closure cap unit includes
1. manually operable unlatching means for moving the said lower and latching end portions of the said flexible, resilient latching members out of the said latching recesses and into the said guide slots whereby the said closure cap unit may be removed from the said neck portion of the said container body by imparting rotational movement thereto in a direction opposite to the direction of movement of the said first rotational movement. 50
- 45
8. A combination container and closure cap unit therefor as defined in claim 7 in which
- a. the said curvilinear cam surfaces are disposed axially above the said curvilinear guide slots on the said neck portion of the said container body. 60
9. A combination container and closure cap unit as defined in claim 7 in which the said closure cap unit includes
- a. manually operable restraining means for controlling manual movement of the said manually operable unlatching means. 70
10. A combination container and closure cap unit therefor as defined in claim 7 in which the said closure cap unit includes

- a. a generally cylindrical housing including
1. a generally annular side wall; and
2. a top wall; and in which the said manually operable unlatching means for manually moving the said lower and latching end portions of the said flexible, resilient, latching members out of latching engagement in the said latching recesses and into the said guide slots on the said neck portion of the said container includes
- a. the said top wall of the said closure cap housing; and in which
3. the said closure cap unit includes
- a. a plurality of manually operable restraining means arranged at circumferentially spaced intervals on the said generally annular side wall of the said closure cap housing for restraining and controlling manual movement of the said manually operable unlatching means including movement of the said top wall of the said closure cap housing.
11. A combination container and closure cap unit therefor as defined in claim 6 in which the said neck portion of the said container body has
- a. an upper edge portion; and in which the said closure cap unit includes
1. a generally cylindrical closure cap housing including
- a. a generally annular side wall;
- b. a top wall; and
- c. a transverse or horizontal sealing wall extending across the said closure cap housing below the said top wall thereof; and in which the said neck portion of the said container body includes
1. a pair of curvilinear cam surfaces each formed as an edge portion of one of the said guide slots and coacting with the said guide means on the said closure cap unit to cam the said transverse or horizontal sealing wall of the said closure cap housing into sealing engagement with the said upper edge portion of the said neck portion of the said container body when the said closure cap unit is installed upon the said neck portion of the said container and rotational movement is imparted thereto.
12. A combination container and closure cap unit therefor comprising
- a. a container body having
1. an upper end portion;
- b. a closure cap unit adapted to be detachably mounted on the said container body;
- c. a first latching means on the said upper end portion of the said container body;
- d. the said closure cap unit including a second latching means coacting with the said first latching means to detachably latch the said closure cap unit to and upon the said upper end portion of the said container body when the said closure cap unit is inserted and rotational movement is manually imparted to the said closure cap unit upon and relative to the said upper end portion of the said container body;
- e. the said closure cap unit including
1. manually operable unlatching means for moving the said second latching means on the said closure cap unit out of latching engagement with the said first latching means on the said upper end portion of the said container body; and
- f. the said closure cap unit including
1. manually operable restraining means normally restraining movement of the said manually operable unlatching means into effective or unlatching position
- whereby the said closure cap unit may be removed from the said upper end portion of the said container body only by applying manual pressure simultaneously to the said manually operable unlatching means and to the said manually operable restraining means and manually imparting rotational movement to the said closure cap unit in a direction opposite to the direction of the said first rotational movement of the said closure cap unit upon and relative to the said upper end portion of the said container body.

13. A combination container and closure cap unit therefor as defined in claim 12 in which
- the said manually operable unlatching means and the said manually operable restraining means are spaced from each other on the said closure cap unit.
14. A combination container and closure cap unit therefor as defined in claim 12 in which
- the said manually operable restraining means includes
  - a plurality of manually operable restraining members spaced from each other and from the said manually operable unlatching means on the said closure cap unit.
15. A combination container and closure cap unit therefor as defined in claim 12 which includes
- means for drawing the said closure cap unit into sealing engagement with the said upper end portion of the said container body when the said closure cap unit is inserted upon the said upper end portion of the said container body and the said first rotational movement is imparted thereto in installing the said closure cap unit upon and relative to the said upper end portion of the said container body.
16. A combination container and closure cap unit therefor as defined in claim 12 in which
- the said closure cap unit includes
  1. a housing, having
  - a. a top wall; and
  - b. a side wall; and in which the said manually operable unlatching means includes the said top wall of the said closure cap housing; and in which the said manually operable restraining means includes
  - b. a plurality of manually operable restraining members arranged at spaced intervals on the said side wall of the said closure cap housing.
17. A combination container and closure cap unit therefor as defined in claim 16 in which
- the said first rotational movement applied to the said closure cap unit in attaching the said closure cap unit to the said upper end portion of the said container body is in the form of a partial turn or revolution of the said closure cap unit upon and relative to the said upper end portion of the said container body in a direction opposite to the direction of rotational movement applied to the said closure cap unit when installing it upon the said upper end portion of the said container body.
18. A combination container and closure cap unit therefor as defined in claim 17 which includes
- coacting guide means on the said upper end portion of the said container body and on the said closure cap unit for guiding the said closure cap unit during the aforesaid rotational movements thereof into and off from the upper end portion of the said container body and for guiding the said second latching means on the said closure cap unit into coacting latching engagement with the said first latching means on the said upper end portion of the said container body.
19. A combination container and closure cap unit therefor as defined in claim 12 in which
- the said second latching means on the said closure cap housing includes
  1. a plurality of flexible latching members spaced from each other on the said closure cap unit; and in which
  2. the said first latching means on the upper end portion of the said container body includes
  - a. coacting latching elements adapted to be latchingly engaged with the said flexible latching members by flexing movement of the said flexible latching members; and in which
  3. the said container and closure cap unit therefor includes
  - a. flexing means for engaging and flexing the said flexible, resilient latching members during the said first rotational movement applied to the said closure cap unit upon and relative to the said upper end portion of the said container body, whereby when the said

- closure cap unit reaches the end of the said first rotational movement thereof on and relative to the said upper end portion of the said container body the said flexible, resilient latching members will move out of engagement with the said flexing means and move under the force of the tension applied thereto by the said flexing means into latching engagement with the said coacting latching elements on the said upper end portion of the said container body.
20. A combination container and closure cap unit therefor comprising:
- a container body including
  1. an upper end portion;
  - b. a closure cap unit detachable attachable to the said upper end portion of the said container body and including
  1. a closure cap housing;
  - c. a first attaching means on the said upper end portion of the said container body;
  - d. a second attaching means on the said closure cap housing and movable by rotational movement of the said closure cap unit upon and relative to the upper end portion of the said container into coacting attaching engagement with the said first attaching means to detachably attach the said closure cap unit to the said upper end portion of the said container body;
  - e. the said closure cap unit including
  1. a plurality of manually operable means arranged in spaced relationship on the said closure cap housing for moving the said second attaching means out of coacting attaching engagement with the said first attaching means
- whereby the said closure cap unit may be removed from the said upper end portion of the said container body by manually inserting the said closure cap unit upon the said upper end portion of the said container body and manually imparting rotational movement thereto without manipulation of any of the said manually operable means or other parts or instrumentalities on either the said container body other than the said rotational movement manually imparted to the said closure cap unit, and the said closure cap unit may be manually removed from the said upper end portion of the said container body by simultaneously applying manual pressure to the said plurality of manually operable means and imparting rotational movement to the said closure cap unit upon and relative to the said upper end portion of the said container body.
21. A combination container and closure cap unit therefor as defined in claim 20 in which the said
- rotational movement imparted to the said closure cap unit in removing it from the said upper end portion of the said container body is in a direction opposite to the direction of the said rotational movement imparted to the said closure cap unit in attaching it to the said upper end portion of the said container body.
22. A combination container and closure cap unit therefor comprising:
- a container body including
  1. an upper end portion;
  - b. a first attaching means on the said upper end portion of the said container body;
  - c. a closure cap unit detachably attachable to the said upper end portion of the said container body and comprising:
  1. a closure cap housing including
  - a. an outer closure body member having therein
  1. a cavity
  - b. an inner closure body member arranged in the said cavity of the said outer body member;
  2. a second attaching means on the said inner closure body member and adapted to have coacting attaching engagement with the said outer closure body member for attaching the said closure cap unit to the said upper end portion of the said container body by rotational movement of the said closure cap unit upon and relative to the said upper end portion of the said container body;

3. manually operable means including
- a. a wall portion of the said inner closure body member for manually moving the said second attaching means on and relative to the said closure cap housing and relative to the said first attaching means to move the said second attaching means out of coacting attaching engagement with the said first attaching means; and
4. manually operable restraining means for preventing manual movement of the said manually operable means whereby the said second attaching means may be manually moved out of coacting attaching engagement with the said first attaching means and the said closure cap unit may be manually removed from the said upper end portion of the said container body by simultaneously applying manual pressure to the said wall portion of the said inner closure body member and to the said manually operable restraining means while simultaneously imparting rotational movement to the said closure cap unit upon and relative to the said neck portion of the said container body.
23. A combination container and closure cap unit therefor as defined in claim 22 which includes
- a. means for returning the said wall portion of the said inner closure body member and the said manually operable restraining means to their normal or initial positions after each operation thereof.
24. A combination container and closure cap unit therefor as defined in claim 23 in which the said inner closure body member of the said closure cap housing includes
- a. a flexible wall portion; and in which the said restraining means includes
1. a flexible resilient restraining member attached to and movable with the said flexible wall portion of the said inner closure body member.
25. A combination container and closure cap unit therefor comprising:
- a. a closure container body;
- b. a closure cap unit adapted to be mounted upon and detachably attached to the said container body by applying the said closure cap unit upon the said container body and imparting rotational movement to the said closure cap unit upon and relative to the said container body from an initial position to a final and attached position on the said container body;
- c. a first attaching means on the said container body;
- d. a second attaching means on the said closure cap unit coacting with the said first attaching means to attach the closure cap unit to and upon the said container body by applying the said closure cap unit to the said container body and manually imparting rotational movement to the

- said closure cap unit upon and relative to the said container body from the initial position to the said final and attached position;
- e. means for maintaining one of the said attaching means out of coacting attaching engagement with the other one of the said attaching means during the time the said closure cap unit is being rotationally moved from its said initial position to its said final and attached position on the said container and body; and
- f. guide means for guiding one of the said attaching means relative to the other of the said attaching means during the time the said closure cap unit is being rotationally moved from its said initial position to its said final and attached position upon and relative to the said container body.
26. A combination container and closure cap unit therefor as defined in claim 25 which includes
- a. manually operable means for moving one of the said attaching means out of coacting attaching engagement with the other of the said attaching means and into the said guide means
- whereby the said closure cap unit may be manually removed from the said container body by imparting rotational movement thereto from its said final and attached position to its said initial position with the said one of the said attaching means moving through the said guide means.
27. A combination container and closure cap unit therefor as defined in claim 27 which includes
- a. means coacting with the said guide means for drawing the said closure cap unit and the said container body together into sealing engagement with each other during the said first rotational movement of the said closure cap unit upon and relative to the said container body.
28. A combination container and closure cap unit therefor as defined in claim 26 in which
- a. the said closure cap unit includes
1. restraining means including manually restraining operable members for restraining movement of the said manually operable means for moving one of the said attaching means out of coacting attaching engagement with the other of the said attaching means
- whereby the said closure cap unit may be manually removed from the said container body only by simultaneously manually operating the said restraining means and the said manually operable means for moving one of the said attaching means out of coacting attaching engagement with the other of said attaching means and manually imparting rotational movement to the said closure cap unit upon and relative to the said container body from the said final and attached position of the said closure cap unit to its said initial position.
